(57) **CLAIM**

I claim the ornamental design for a glove and boot drier, as shown and described.

DESCRIPTION

FIG. 1 is a front elevational view showing my new design, with the back elevational view being identical thereto;
FIG. 2 is a right elevational view thereof, with the left elevational view being a mirror image thereof;
FIG. 3 is a bottom plan view thereof;
FIG. 4 is a top plan view thereof; and,
FIG. 5 is a perspective view thereof.
